(57) CLAIM

The ornamental design for a tire for ordinary cars and golf vehicles, as shown and described.

DESCRIPTION

FIG. 1 is a perspective view of a tire for ordinary cars and golf vehicles, showing my new design;

FIG. 2 is a front view thereof; and,

FIG. 3 is a left view thereof.

The broken lines depict portions of a tire for ordinary cars and golf vehicles in which the design is embodied that form no part of the claimed design.
